UNITED STATES PATENT OFFICE

123,544

DESIGN FOR A SCARF

Gertrude de Postels, New York, N. Y., assignor to Benjamin Wolf Co., Inc., New York, N. Y., a corporation of New York

Application August 17, 1940, Serial No. 94,483

Term of patent 3½ years

To all whom it may concern:

Be it known that I, Gertrude de Postels, a citizen of the United States of America and residing in the city, county, and State of New York, have invented a new, original, and ornamental Design for a Scarf, of which the following is a specification, reference being had to the accompanying drawing, forming part thereof.

The figure is a plan view of a scarf showing my new design.

I claim:
The ornamental design for a scarf, as shown.

GERTRUDE DE POSTELS.
